(57) **CLAIM**

The ornamental design for a floor exercise slider, as shown and described.

DESCRIPTION

FIG. 1 is a top perspective view of a design for a floor exercise slider;

FIG. 2 is a top view thereof;

FIG. 3 is a bottom view thereof;

FIG. 4 is a left side thereof;

FIG. 5 is a right side thereof;

FIG. 6 is a rear view thereof;

FIG. 7 is a front view thereof;

FIG. 8 is a top perspective view showing two floor exercise sliders in a typical environment;

FIG. 9 is a top perspective view showing a first floor exercise slider engaged with a second floor exercise slider;

FIG. 10 is a top view showing the first floor exercise slider engaged with the second floor exercise slider;

FIG. 11 is a bottom view showing the first floor exercise slider engaged with the second floor exercise slider;

FIG. 12 is a left side view showing the first floor exercise slider engaged with the second floor exercise slider;

FIG. 13 is a right side view showing the first floor exercise slider engaged with the second floor exercise slider;

FIG. 14 is a rear view showing the first floor exercise slider engaged with the second floor exercise slider; and,

FIG. 15 is a front view showing the first floor exercise slider engaged with the second floor exercise slider.

In the drawings, the broken lines showing a human in FIG. 8 depict environment and form no part of the claimed design, and the other broken lines in FIGS. 1-15 represent either boundaries of the claimed design forming no part thereof or optional logo placement on the claimed design forming no part thereof.

1 Claim, 10 Drawing Sheets
